WOVEN TEXTILE AND ALUMINUM FABRIC

Maurice Schaller, Clifton, N.J., assignor to Levolor
Lorentzen, Inc., Hoboken, N.J.

Filed Oct. 22, 1971, Ser. No. 191,950

Term of patent 14 years

Int. Cl. D5—05

U.S. Cl. D92—1 Y

FIG. 1

3

FIG. 2

FIG. 3

FIG. 4

FIG. 5

FIG. 1 is a top plan view of a woven textile and aluminum fabric showing my new design;

FIG. 2 is an enlarged top plan view of one repeat unit thereof;

FIG. 3 is a sectional view taken on the line 3—3 of FIG. 2;

FIG. 4 is a plan view of the other side of FIG. 1; and

FIG. 5 is a plan view of the other side of FIG. 2.

I claim:

The ornamental design for a woven textile and aluminum fabric, as shown.
